UNITED STATES PATENT OFFICE.

JOHN E. MARSH, OF MOORCROFT, WYOMING.

FRAME FOR TRACTORS.

1,201,485.

Specification of Letters Patent.

Patented Oct. 17, 1916.

Application filed October 20, 1915. Serial No. 56,941

To all whom it may concern:

Be it known that I, JOHN E. MARSH, a citizen of the United States, residing at Moorcroft, in the county of Crook, State of Wyoming, have invented certain new and useful Improvements in Frames for Tractors; and I do hereby declare the following to be a full, clear, and exact description of the invention, such as will enable others skilled in the art to which it appertains to make and use the same.

This invention relates to frames for tractors.

The object of the invention is to provide an improved frame for tractors which can be secured in place without the necessity of passing bolts or rivets through the firebox or boiler and which will serve as a support for the axle brackets and the countershaft 20 and in addition will form a support for a platform.

A further object of the invention is to provide an improved frame for tractors which will so support the axle brackets and the countershaft as to prevent the greater part of the strain of the countershaft and the wheels on the axle bracket being transmitted to the firebox or boiler.

With the above and other objects in view the invention consists in the details of construction and in the arrangement and combination of parts to be hereinafter more fully described and particularly pointed out in the appended claims.

35 In describing the invention in detail reference will be had to the accompanying drawings wherein like characters of reference denote corresponding parts in the several views, and in which—

40 Figure 1 is a side elevation of a tractor having the improved frame associated therewith; Fig. 2, a plan view of what is shown in Fig. 1 partly in section; Fig. 3, a plan view of the rear portion of the frame; Fig. 4, a horizontal section through the rear portion of the frame; Fig. 5, a section on the line 5—5 of Fig. 1; Fig. 6, a section on the line 6—6 of Fig. 2; Fig. 7, a partial rear view of the frame, and Fig. 8, a perspective 50 view of the draw bar employed in connection with the frame.

Referring to the drawings A indicated the rear portion of a tractor wherein is included a boiler 10 and a firebox 11.

55 The improved frame is shown as comprising side sections B and C each of which is

formed of an upper member 12 and a lower member 13 of channel iron. The forward end of the member 13 extends upwardly as at 14 and is bolted to the member 12. The 60 rear ends of the members 13 are bent inwardly to form loops 15 and 16 and the ends of said members are connected by a bar 17. Secured between the bars 17 and the ends of the members 13 is the head 18 of a draw 65 bar 19 said head and bar being substantially housed in the channels of the members 13. This bar 19 extends through a cross beam 20 which latter is also connected to the rear ends of the members 13 within the limits 70 of the loops 15 and 16. The beam 20 is also connected to the members 13 by means of braces 21. Supported upon the rear ends of the members 13 and suitably secured to the latter is a platform 22. Mounted upon 75 the forward ends of the members 12 is a cross beam 23 and the extreme forward ends of these members 12 are connected by a brace 24. Suitably bolted to the members 12 and 13 of each section A and B is an axle 80 bracket 25 having engaged thereon the clamp ends 26 of a binding rod 27 which latter extends over the top of the fire box 11, it being understood that the rod 27 has each end terminating in a clamp for connection with 85 one of the axle brackets. Each axle bracket 25 is strengthened by braces 28 and 29 which connect same with the beam 23 and the rear end of the firebox 11 respectively. Each 90 axle bracket 25 is also connected to the related member 13 by means of a brace 30. The members 13 of the sections A and B are connected by means of a plurality of binding rods 31 which extend beneath the firebox 11, said rods 31 in connection with the 95 rod 27 serving to hold the frame in place upon the tractor firebox as will be obvious. The ends of the beams 20 and 23 and the axle brackets 25 are connected by bars 33. These bars can be dispensed with when using 100 the tractor for lighter work such as threshing although they are desirable in plowing and other heavy work. The main purpose of these bars 33 is to serve as an additional safeguard in strengthening the structure as 105 a whole.

What is claimed is:—

1. A tractor frame comprising side sections each of which includes upper and lower members, cross bars connecting the 110 upper members and the lower members, an axle bracket connecting the upper and lower

members of each section, a binding rod having its ends terminating in clamps engageable over the top portion of the firebox of a tractor, and binding rods connecting the lower members of the sections and engageable beneath the firebox of a tractor.

2. A tractor frame comprising side sections each of which includes upper and lower members formed of channel iron, the lower members of the sections being extended at one end and bent inwardly to form loops, a bar connecting the rear ends of the lower members, a draw bar having

a head secured between the first named bar and the inner ends of the lower members and 15 further having a stem substantially housed in the channels of the lower members, a cross bar connecting the upper members of the sections, and means for securing the sections to the firebox of a tractor.

In testimony whereof, I affix my signature, in the presence of two witnesses.

JOHN E. MARSH.
